UNITED STATES PATENT OFFICE.

EDWARD KENDALL, OF CAMBRIDGEPORT, MASSACHUSETTS.

APPARATUS FOR HEATING AIR OR CONDENSING STEAM.

SPECIFICATION forming part of Letters Patent No. 272,886, dated February 27, 1883.

Application filed November 9, 1882. (No model.)

To all whom it may concern:

Be it known that I, EDWARD KENDALL, of Cambridgeport, in the county of Middlesex and State of Massachusetts, have invented 5 certain new and useful Improvements in Apparatus for Heating Air or Condensing Steam, of which the following, taken in connection with the accompanying drawings, is a specification.

10 My invention relates to an apparatus which may be termed an "air surface-condenser" or an "air-heater," and has for its object the utilization of exhaust-steam for heating air to be used in warming buildings, or for supplying 15 pure water by condensation of the steam for feeding steam-boilers; and it consists in certain novel features of construction, arrangement, and combination of the parts of the apparatus, which will be readily understood by 20 reference to the description of the drawings, and to the claim to be hereinafter given.

Figure 1 of the drawings is a plan of my improved apparatus with the upper covering-plate removed and a portion of the upper head 25 of the steam-chamber broken away, and showing the air-tubes and the partitions in section on line *x x* on Fig. 2; and Fig. 2 is a vertical section of the same on line *y y* on Fig. 1.

30 A and A' are two castings, preferably oval in plan, and each composed of a head, *a*, vertical wall *b*, and cross-partitions *c*.

B and B' are detachable covers, secured to the castings A and A', respectively, by means of suitable bolts, which screw into the wall *b* and partitions *c*, thus forming air-tight joints 35 between said covers and the castings A and A', and forming in each of said castings a series of chambers, *d*, *e*, *f*, and *g*, or *d'*, *e'*, *f'*, and *g'*. The heads *a* of the castings A and A' are perforated to receive the ends of a series of clusters, C, C', C², C³, C⁴, C⁵, and C⁶, of small pipes, so set therein as to form steam-tight joints, and to help to maintain said heads at the proper distance apart. The castings A and A' are 40 further connected together by the casing D, of plate-iron, firmly riveted thereto and calked, so as to form steam-tight joints, and inclosing the steam-chamber E, across which the clusters of small pipes extend, as shown.

45 F is a steam-inlet pipe, which may be con-

nected with the exhaust-pipe of a steam-engine or other steam-supply, as may be desired; and F' is the steam-discharge pipe, and G is a valve or gate, by means of which said discharge-pipe may be closed or opened at will. 55

H is a pipe connected by the branches *h*, *h'*, *h²*, and *h³* with the interior of the steam-chamber E, and leading to and communicating with the interior of the hot-well I, into which the water produced by condensation of the steam 60 flows, and from which it may be pumped to any desired point by the pump J.

I prefer to use air instead of water as a medium for condensing the steam; and to this end I provide the casting A with an air-inlet 65 orifice, K, of large area, and connect therewith the pipe K', leading to the blower L, by means of which a current of cold air may be forced at considerable speed into the chamber *d*, cluster of pipes C, chamber *d'*, cluster 70 of pipes C', chamber *e*, cluster of pipes C², chamber *e'*, cluster of pipes C³, chamber *f*, cluster of pipes C⁴, chamber *f'*, cluster of pipes C⁵, chamber *g*, cluster of pipes C⁶, chamber *g'*, and the discharge-orifice M, in the end of the 75 casting A' opposite to the inlet-orifice K, into the open air, if the apparatus is being used as a condenser; or it may be conveyed by suitable pipes to any desired point for heating rooms, if desired. 80

The steam-chamber E is divided into several compartments by two sets of partitions, N and O, the former rising from the bottom to near the top of the chamber E and the latter depending from the top to near the bottom of the chamber E in such a manner that steam entering at F will completely envelop the cluster C⁶ of small pipes, be compelled to rise to the top of the chamber E, to pass over a partition, N, and then pass downward to the bottom of chamber E, completely enveloping the cluster C⁵ of the pipes, to pass beneath the partition O to the next compartment, and so on till it has filled the chamber E and completely enveloped all parts of all of the pipes 95 in the several clusters.

The operation of my invention is as follows: If it is desired to use it as a condenser, the valve or gate is closed, steam is admitted at F, and the blower L is set in motion to force a 100

current of cold air through the several chambers d , e , f , g , d' , e' , f' , and g' and the several clusters of pipes C , C' , C^2 , C^3 , C^4 , C^5 , and C^6 , as before described. The pipes through which 5 the cold air passes take up the heat from the surrounding steam, and thus condense it, and the water resulting from said condensation falls to the bottom of the chamber E , and flows through the pipes h , h' , h^2 , h^3 , and H to 10 the hot-well I , from which it is discharged by the pump J , through suitable pipes, to the interior of the boiler, to be again made into steam.

By using air instead of water for condensing the steam the water resulting from such condensation is free from lime and other impurities which enter into and form a part of most waters in their natural state, and hence is better suited for feeding steam-boilers.

If it is desired to use this apparatus for heating air for use in warming buildings, the air-discharge orifice M is connected by suitable pipes with the rooms to be heated, the valve or gate G is opened, and the blower L is set in motion to force the air through the several clusters 20 of pipes in succession, said air in its passage being exposed to and taking up a portion of the heat from the hot steam flowing through the chamber E and surrounding the several 25 clusters of pipes.

By this arrangement fresh, pure air heated 30 to the desired temperature may be supplied to factories and manufacturing establishments at a very trifling cost.

What I claim as new, and desire to secure by Letters Patent of the United States, is— 35

The combination of the steam-chamber E , provided with the partitions N and O , and a steam-supply pipe, two series of air-chambers arranged upon opposite sides of said steam-chamber, a series of clusters of pipes connecting 40 said air-chambers, means of forcing air through said air-chambers and series of clusters of pipes, the pipe H , one or more pipes connecting said pipe with the interior of the steam-chamber E , and the pump J , all arranged and adapted to operate substantially 45 as and for the purposes described.

In testimony whereof I have signed my name to this specification, in the presence of two subscribing witnesses, on this 4th day of November, 50 A. D. 1882.

EDWARD KENDALL.
